UNITED STATES PATENT OFFICE

JOHN M. SHIELDS, OF CHICAGO, ILLINOIS, ASSIGNOR TO F. H. NOBLE & COMPANY, OF CHICAGO, ILLINOIS, A CORPORATION OF ILLINOIS

WRIST-WATCH BOX

Application filed July 12, 1928. Serial No. 292,047.

My invention relates to a box or case designed particularly for the reception of a wrist watch and attached strap, of leather or similar material, and the object is to provide a container suitable for the display of the watch when offered for sale or receiving the watch when not in use which shall have convenient means for engaging and confining in position the strap members, whereby the watch is neatly held in position within the box without liability of the back of the watch becoming marred, and the open box may be freely handled without danger of the watch dropping out. My invention resides in the novel construction and arrangement of the lining members of the box, as hereinafter fully described and explained, the essential elements thereof being more particularly pointed out in the appended claims.

20 In the drawing,

Figure 1 is a view in perspective showing my novel wrist watch box with the cover open and a watch within the box;

Fig. 2 is a plan view of the false bottom structure of the box to which my invention more particularly relates;

Fig. 3 is a longitudinal section of said structure in a plane indicated by the dotted line 3—3 of Fig. 2;

30 Fig. 4 is a plan view of the cardboard member of said false bottom structure, and

Fig. 5 is a fragmentary plan view of one end of such structure.

The same reference characters are used to 35 severally designate the same parts in all the figures of the drawing.

The box body 1, and lid 2, hinged to the body, may be conveniently formed of sheet metal, covered with an ornamental fabric, 40 as usual in such articles, the inside of the cover being in the present instance lined and the hinge covered with fabric to form a neat finish. The body of the box may be provided, as shown, with a fabric covered lining strip 45

3 extending around the inside of its sides and ends, and the bottom covered with a rectangular lining strip 4, all these lining and finishing members being secured to the sheet metal box parts by a suitable adhesive.

50 The parts to which my invention more par-

ticularly relates include a somewhat thick cardboard false bottom member 5 which is cut out longitudinally of the box along its central region, though not necessarily along its mathematical center line, to provide a 53 strap-receiving slot or pocket marked 6 which at one end is preferably slightly enlarged as indicated by the reference numeral 7 and a covering 8 of velvet, or similar material cemented thereto. In the present instance, 60 the velvet covering is carried around the edges of the false bottom and a finishing sheet of paper 9 is cemented to the under side thereof.

The rear edge of the false bottom member 65 is slightly cut back adjacent the hinge line as indicated at 10, to accommodate the roll of the hinge members, and a tab of ribbon 11 may be secured to the false bottom, as shown, to enable it to be readily removed from the 70 box, if desired.

Opposite the enlarged portion 7 of the pocket within the false bottom, and a short distance from what I will term the outer end of the pocket, the cover 8 is slotted in such 75 manner as to provide an orifice 12 through which the perforated section of the strap 13 of the wrist watch 14 may be inserted so that it will lie underneath the fabric within the pocket, while the body of the watch lies on top 80 of the fabric opposite the enlarged portion of the pocket, and the portion of the strap 15 to which the buckle is secured extends along the upper face of the velvet covering. An overhanging clip 16, which may be covered with 85 fabric similar to the covering 8, serves to hold buckle-carrying section 15 of the strap against the false bottom structure. The velvet above the pocket 7 (occupied in part by the strap 13) is to some extent free to yield, 90 and form a seat for the watch and for the strap 15 below the plane of the upper face of the false bottom member 5, over which the velvet is smoothly stretched.

The attachment of the buckle-carrying section of the strap by the clip 10 at one side of the watch, and of the perforated section at the opposite side by passing it through the orifice 12 of the velvet covering adjacent such opposite side of the watch, provides means 95

whereby the watch is securely held on the yielding expanse of the velvet covering opposite the cut out opening of the false bottom member so that it cannot shake around in the box while being handled or during shipment, and as the false bottom structure is a finished unit, it may be removed for display purposes, or in case it is desired to use the box for other purposes.

10 I claim:

11 1. A wrist watch container including a box body, and a false bottom structure therein including a false bottom member cut out along its central region and an orificed fabric cover member providing a strap-receiving pocket, the cut-out opening in said bottom member being enlarged adjacent its outer end and the orifice in said fabric member being formed adjacent such outer end, whereby the body of a wrist watch arranged in said box will rest upon the upper face of the fabric cover member opposite said enlarged end of the opening in the body member and the perforated section of the strip will be received 25 within said pocket underneath said fabric member.

26 2. A wrist watch container including a box body, a false bottom structure therein including a false bottom member cut out along 30 its central region and an orificed fabric cover member providing a strap-receiving pocket, the cut-out opening in said bottom member being enlarged adjacent its outer end and the orifice in said fabric member being formed 35 adjacent such outer end, whereby the body of a wrist watch arranged in said box will rest upon the upper face of the fabric cover member opposite said enlarged end of the opening in the body member and the perforated section of the strip will be received within said pocket underneath said fabric member, and 40 means for securing the buckle-carrying end of said strap to the face of said false bottom structure.

45 3. A container for wrist watches and like articles including a box body and a false bottom structure therein including a false bottom member cut out along its central region and an orificed fabric cover member providing a strap receiving pocket, an orificed opening provided by said fabric member being situated adjacent the outer end of the cut out opening of the false bottom member, whereby the wrist watch arranged in said box will 50 rest upon the upper face of the fabric member opposite the cut out opening in the bottom member and will be cushioned thereby and the perforated section of the strap will be received within said pocket underneath said 55 fabric member to constrain the watch against movement when handled or during shipment.

60 4. A container for wrist watches and like articles comprising a body member and a false bottom structure therein including a 65 false bottom member cut out along its central

region to define an elongated slot, a fabric member secured to said false bottom structure and overlying the slot formed therein, said slot constituting a pocket for receiving the watch whereby the same will rest upon and be cushioned by the upper face of the fabric cover member extending across the slot, and an orifice provided by said cover member for receiving a strap secured to the wrist watch and constrain the watch from relative movement with respect to the false bottom member when handled or in transit.

70 In testimony whereof, I have subscribed my name.

JOHN M. SHIELDS.
